[57] CLAIM

The ornamental design for a ribbon, as shown.

DESCRIPTION

FIG. 1 is a top plan view of a ribbon showing our new design, the rear plane view being substantially a mirror image thereof; and,

FIG. 2 is an end elevation of FIG. 1 taken from either end of FIG. 1.

The pattern continues along either or both the major and/or minor dimension(s).

FIG. 1

FIG. 2
